CABINET

Edgar W. Roehm, 1133 Burdsal Parkway,
Indianapolis, Ind.

Filed Apr. 6, 1959, Ser. No. 55,364

Term of patent 14 years

(Cl. D33—19)

FIG. 1

FIG. 2

FIG. 3

FIG. 4

FIG. 5

FIG. 6

Fig. 1 is a front elevational view of a cabinet embodying my new design;

Fig. 2 is a side elevational view thereof;

Fig. 3 is a top plan view thereof;

Fig. 4 is a perspective view of the top drawer on the base portion of said cabinet;

Fig. 5 is an enlarged fragmentary view of the pulls of said drawer; and

Fig. 6 is a side elevational view thereof.

The back of the article is conventionally plain.

I claim:

The ornamental design for a cabinet, substantially as shown and described.
